UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed May 5, 1922. Serial No. 558,652.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to front-strike type-
writing machines and particularly to devices
10 for guiding cards, labels and comparatively
small work-pieces, around the platen and for
holding them in typing position.

An object of the invention is to produce
15 a highly effective device which is readily at-
tachable to the machine. A particular ob-
ject of the invention is to hold the card or
label or other work-piece firmly against the
platen throughout its vertical length adja-
20 cent the side margins thereof, so that, if de-
sired, a line may be typed closely adjacent
to either the top or bottom edge of the
work-piece. Another object of the inven-
tion is to render the device readily adjust-
25 able for holding the side margins of work-
pieces of various sizes. Another object of
the invention is to produce a card-holding or
label-holding device which co-operates with
features of the typewriting machine as origi-
30 nally built without said device, and more
particularly a device adapted to be installed
upon and co-operate with the usual features
of construction of an Underwood standard
portable typewriting machine.

35 The invention comprises curved paper-
holding guide-fingers extending downward
at the front of the platen and slidably
mounted at their upper ends upon a bar ex-
tending along the top of the platen and de-
40 tachably mounted upon the platen-frame.
More particularly, said paper-holding guide-
fingers may be in the form of small or thin
spring wires carried by slides which are non-
rotatably mounted to slide along said bar.

45 Also, according to the present invention, the
means for detachably supporting said finger-
carrying bar upon the platen-frame may
comprise a bracket rigidly secured to each
50 end of the bar, the rear end of each bracket
being detachably mounted on the platen-
frame at the rear of the platen, and the
front end of each bar-supporting bracket
55 being detachably connected to the upper end
of the adjacent one of the usual upwardly-
extending paper-fingers at the front of the

platen, such paper-fingers being commonly
employed for pressing ordinary work-sheets
against the front of the platen. More par-
ticularly, each said bracket at its rear end
may be provided with a hook or prong to 60
removably enter a socket provided on the
platen-frame, and at its front end said
bracket may be provided with a catch or
hook forming a recess open at the front to
engage or receive therein the small paper- 65
holding roll commonly provided upon the
upper end of each of said paper-fingers.

Other features and advantages will here-
inafter appear.

In the accompanying drawings, 70
Figure 1 is a front elevation, with parts
broken away, of the upper part of an Under-
wood standard portable typewriting ma-
chine having the device embodying the pres-
ent invention installed thereon. 75

Figure 2 is a front-to-rear vertical sec-
tion, with parts in side elevation, of what
appears in Figure 1, together with some
additional parts.

Figure 3 is a side elevation, partly in 80
section, and with parts omitted.

Figure 4 is a plan view of what appears
at the left in Figure 1.

Figure 5 is a view similar to Figure 3, 85
illustrating the manner in which the device
of the present invention may be attached to
or detached from the machine.

Figure 6 is an enlarged perspective view,
showing one of the finger-carrying slides 90
and the corresponding paper-holding guide-
finger separate therefrom.

In order clearly to understand the present
invention, it will be necessary first to de-
scribe the associated and the co-operating
parts or features of the Underwood stand- 95
ard portable typewriting machine, upon
which the illustrated embodiment of the in-
vention is shown as installed in the accom-
panying drawings.

The platen-frame, which, in said machine, 100
also forms a traveling carriage, comprises a
lower transverse bar or plate 1 and an L-
shaped rear transverse bar or rail 2, which
connect together end plates 3, shown as se-
cured to the ends of the lower bar 1, by 105
means of screws 4 and to the ends of the rear
bar 2 by means of screws 5. The cylindrical
platen 6 has its axle 7 journaled in the end
plates 3 and at its right-hand end the platen-
axle 7 is provided with a finger-wheel 8 for 110

turning the platen. For guiding work-sheets around the platen a usual paper-guide 9 is provided, which at the rear of the platen forms an inclined rear paper-table which is curved to form a paper-apron beneath the platen, and at its forward end the paper-guide 9 carries a usual feed-roll 10, to run upon the front part of the bottom of the platen. Commonly the paper-guide 9 is pivoted upon the platen-frame (by means not shown), so as to rock on its pivots for releasing or casting off the feed-roll 10 from the platen, to provide for the free insertion and adjustment of work-sheets, and springs 15 (not shown) are provided to act upon the paper-guide 9 for pressing the feed-roll 10 towards the platen. Also a cast-off device for the feed-roll 10 is commonly provided to act upon the paper-guide 9, parts of which are not shown, but the rock-shaft 11 of which appears in Figure 2, lying within an angle formed by the rear bar 2 of the platen-frame.

A sheet-guiding bar 12, of angular inserted V-shape and formed of sheet-metal, extends transversely along the front of the platen below the printing line forwardly from and above the feed-roll 10, and along its forward face has graduations providing a letter-space scale, as shown in Figure 1. At its ends the sheet-guiding scale-bar 12 fits over, and, by means of screws 13, is secured to upwardly-projecting wedge-shaped ends 14 of forwardly and upwardly extending inclined arms 15, which, at their lower or rear ends, are pivoted in the end plates or end walls 3 of the platen-frame by means of pins of studs 16. For pressing the paper-guiding scale-bar 12 towards the platen, leaf-springs 17 are secured at their lower ends to the scale-bar 12, and also to the lever-ends 14, by means of the screws 13, and the springs 17, at the upper ends, bear against the inner sides of inturned circularly curved flanges 18 provided upon the platen-frame end walls 3.

A finger-supporting rod 19 is fixed at its ends in the pivoted arms 15 at the bases of the wedge-shaped ends 14. Upstanding or upwardly-projecting resilient paper-fingers, formed of sheet-metal, at their lower in-turned ends 21 are turned about the transverse finger-supporting rod 19, and these ends 21 are provided with upwardly-projecting tongues 22 which bear against the adjacent rear face of the inner side of the V-shaped scale-plate or bar 12 to prevent rotative movement of the paper-fingers 20 on its supporting rod 19. A small paper-holding roll 23 is mounted, by means of a pivot-pin 24, between rearwardly-projecting ears 25 on the upper end of each paper-finger 20. The roll 23 will be resiliently pressed against the platen, or against a work-sheet thereon, both by the resilient pa-

per-finger 20 and by the leaf-springs 17 of the sheet-guiding scale-bar 12.

The platen-frame, which forms also a carriage, may have traveling letter-feeding and return movement upon a shift-frame 26. For this purpose, the shift-frame is provided with a lower or front rail 27 upon which the lower bar 1 of the platen-frame may travel by means of interposed bearing-balls 28, and the shift-frame 26 also has a rear rail 75 (not shown), and the rear bar 2 of the platen-frame is provided with a roller (not shown) to travel along the rear rail of the shift-frame.

An upstanding resilient sheet-metal plate 29 is secured at its lower end to the lower rail 27 of the shift-frame 26 by means of screws 30 and its upper end part forms wing-scales 31 between which there is provided a slot 32 through which the types carried by type-heads 33 (Figure 2) may print at the printing point on the front of the platen, the upper end of the plate 29 being provided at one side of the slot 32 with a slightly rearwardly-curved upwardly-projecting finger 34 for pressing a work-piece against the platen in close proximity to the printing point.

The construction as so far described is that heretofore commonly employed in the Underwood standard portable typewriting machine. The illustrated embodiment of the card-holding and label-holding device or attachment forming the subject of the present invention, and its relationship to the above-described associated parts of the machine with which it co-operates, will now be described.

According to the present invention a stiff or rigid finger-carrying bar 35 is provided to be firmly but detachably mounted upon the platen-frame to extend along the top of the platen parallel thereto forwardly of the top line thereof, as shown in Figures 1, 2 and 3. This finger-carrying bar 35 may be formed of a strip of comparatively heavy sheet-metal and is shown as arranged radially of the platen 6, so as to be slightly inclined forwardly. In order to increase the stiffness or rigidity of the finger-carrying bar 35, it is shown as provided with a rearwardly-projecting longitudinal stiffening rib 36. Each end of the finger-carrying bar 35 is firmly secured, by means of screws 37, to a bracket 38, provided at the lower edge of the bar or bridge 35, with a rearwardly extending arm 39, and provided at the upper edge of said bar or bridge with a front downward extension 40. Each bracket-arm 39 terminates in a downwardly and rearwardly turned hook or prong 41 which is removably engageable in a hole 42 forming a socket at the upper end of each of right and left substantially Z-shaped bracket-members 43 and 44 secured at their lower ends to the 130

rear carriage-rail 2 by means of screws 45 and 46, the right bracket-member 43 being somewhat shorter and held above the hereinbefore-mentioned feed-roll cast-off shaft 5 11 by means of a small spacing block 47, as shown in Figures 1 and 2. The screws 45 and 46 also assist the screws 5 in securing together the rear bar 2 and the end walls 3 of the platen-frame. The front extension 40 10 of each bar-supporting bracket 38 terminates at its lower end in a substantially semi-circular hook or catch 48, entrance of which is at the front to receive therein and be securely held by the small paper-holding roll 15 23 on the corresponding paper-finger 20 when sprung away from the platen, as shown in Figures 1, 2, 3, and 4, so that the paper-fingers 20 and the brackets 38 have a releasable interlocking engagement. It will be 20 noted that, according to the present invention, the usual paper-fingers 20 form upstanding resilient bracket-holding members at the front of the platen. The upper end of each paper-finger 20 is provided with a 25 finger-piece 49 to enable the paper-finger 20 to be conveniently sprung away from the platen.

Two resilient paper-holding guide-fingers 50 at their upper ends are slideable but non-30 rotatably mounted upon the finger-carrying bar 35, so to be independently adjustable along the platen, and extend downwardly in curved relation around the front of the platen below the printing line thereon and 35 terminate below and at the rear of the upper edge of the paper-guiding scale-bar 12. In order that the guide-fingers 50 may occupy as little space as possible upon the work-piece held to the platen thereby, so as to 40 permit typing upon the work-piece close to to the side edges thereof, these fingers 50 are formed of thin spring wire. The means for mounting the guide-fingers 50 upon the finger carrying transverse bar 35 comprise, 45 for each said finger, a sleeve-like slide 51 which may be formed of suitable sheet-metal to embrace the bar 35, as shown in the drawings. At the front of the bar 35 each slide 51 is provided with a plurality of bendable 50 lugs or tabs 52 shown as four in number, which may be clinched down upon the side members of a rectangular eye 53 formed upon the upper end of the guide-finger 50, so as thereby firmly to secure the guide-finger 55 50 at its upper end to the slide 51. At the rear of the bar 35 each end of the slide 51 is provided with a projecting wing 54 forming finger-pieces by which the slide 51 may be conveniently slid along the bar 35 to 60 adjust the guide-fingers 50 along the platen 6. The lower ends of the guide-fingers 50 are turned slightly outward at 55 so as to clear the leading edge of a work-piece as it is advanced around the platen.

65 In order to attach the device of the pres-

ent invention to the machine, it is only necessary first to insert the hooks 41 downwardly in the socket-providing holes 42 in the upper ends of the upstanding bracket-members 43 and 44 and then rock or swing 70 the device forwardly, as shown in Figure 5, to bring the front hooks 48 over and into proximity to the small rolls 23 on the upper ends of the paper-fingers 20, and the paper-fingers, by means of their finger-pieces 49, 75 may be sprung outward by a hand of the typist at each side of the machine, for bringing the rolls 23 and hooks 48 into engagement, as shown in Figures 1, 2, 3 and 4. The entire device will then be firmly and 80 rigidly held in position on the machine, it being noted in this connection that the resilient upstanding paper-fingers 20 are substantially rigid in a vertical direction, so as thereby effectively to prevent vertical play 85 of the device at the front of the machine, while at the rear the hooks 41 are securely locked to the respective bracket-members 43 and 44. To prepare the machine for writing upon ordinary work-sheets, it is only 90 necessary to reverse the above-described operation, that is to say, first to release the paper-finger rolls 23 from the front hooks 48, as shown in Figure 4, and then the entire device may be tilted or rocked rearwardly and the rear hooks 41 lifted out of the socket-openings 42. The usual paper-fingers 20 will then be free to be adjusted along the platen and may be employed in the usual way to hold work-sheets against 95 the platen by means of their rolls 23.

In using the card-holding or paper-holding device of the present invention, a comparatively small work-piece, such as a card 56, shown in Figures 1 and 3, or a thin paper 100 label, may be inserted in the machine at the rear of the platen over the rear paper-table and paper-apron provided by the paper-guide 9, and by rotating the platen by means of the knob or finger-wheel 8, the work-piece 105 may be advanced to typing position at the front of the platen, passing beneath the resilient paper-holding guide-fingers 50, which press the work-piece firmly and smoothly 110 against the platen, both by reason of their own resiliency and also by reason of the fact that the lower ends of the guide-fingers 50 are pressed towards the platen by the resiliently-mounted scale-bar 12, as shown in Figures 1 and 3. In case typing is to be 115 done upon a comparatively thick or stiff card, such as the card 56, the curved guide-fingers 50 will be effective to bend the card smoothly around the front of the platen, and as the leading edge of the card is advanced 120 beyond these fingers to the rear, the card, because of its stiffness, will have a tendency to resume its flat condition, as shown by the upper margin of the card 56 in Figures 1 and 3. Should the work-piece be a label 125 130

composed of thin, weak or flimsy paper, the curved guide-fingers 50, closely hugging the front of the platen, will be effective to hold such weak paper label smoothly upon the platen. By reason of the fact that the guide-fingers 50 engage only the side margins of the work-piece, leaving both the leading edge and the trailing edge thereof free, typing may be done along the top 10 margin of the work-piece very close to its leading edge and also similarly along the bottom margin very close to its trailing edge, as is shown by the word "The" typed close to the lower edge of the card 56, in Figure 1. Also by reason of the fact that the thin wire guide-fingers 50 occupy but very little lateral space, these fingers may be adjusted very close to the side edges of the work-piece, so that a line of writing may begin very close to the side edge at the left 20 and end very close to the side edge at the right of the work-piece, as will be clear from an inspection of Figure 1.

Variations may be resorted to within the scope of the invention, and portions of the improvements may be used without others.

Having thus described my invention, I claim:

1. In a front-strike typewriting machine, 30 the combination with a platen-frame and a revoluble platen journaled therein, of a finger-carrying bar mounted on the platen-frame, including engaging means at the front of said frame for holding the bar rigidly in place, and extending along the top of the platen parallel thereto, and a resilient paper-guiding and paper-holding finger 35 slidable on said bar so as to be adjusted along the platen, said finger extending downward in curved relation around the front of the platen.

2. In a front-strike typewriting machine, 45 the combination with a platen-frame and a revoluble platen journaled therein, of a finger-carrying bar mounted on the platen-frame, including engaging means at the front of said frame for holding the bar rigidly in place, and extending along the top of the platen parallel thereto, a slide 50 slidable along said bar, and a relatively thin spring-wire paper-guiding and paper-holding finger fixed at its upper end upon the slide and extending downward in curved relation around the front of the platen, to be adjusted along the platen with said slide.

3. In a front-strike typewriting machine, 60 the combination with a platen-frame and a revoluble platen journaled therein, of a finger-carrying bar rigidly mounted on the platen-frame and extending along the top of the platen parallel thereto, a slide slidable along and non-rotative upon said bar, and a spring-wire paper-guiding and paper-holding finger extending downward at the 65 front of the platen and curved to the con-

tour of the platen, said finger having an eye or loop at its upper end, said slide being provided with a plurality of bent lugs embracing the wire forming said loop for rigidly securing said finger to said slide to 70 be adjusted along the platen therewith.

4. In a front-strike typewriting machine, the combination with a platen-frame, a revoluble platen journaled therein, and a sheet-guiding bar carried by the platen-frame at the front of the platen below the printing line, of a finger-carrying bar rigidly mounted on the platen-frame and extending along the top of the platen parallel thereto, and a resilient paper-guiding and 75 paper-holding finger non-rotative upon and slidable along the finger-carrying bar so as to be adjusted along the platen, said finger extending downward in curved relation around the front of the platen and passing 80 at its lower end between the platen and said sheet-guiding bar.

5. In a front-strike typewriting machine, the combination with a platen-frame, a revoluble platen journaled therein, and a sheet-guiding bar extending along the front 90 of the platen below the printing line and resiliently mounted on the platen-frame to be pressed towards the platen, of a finger-carrying bar rigidly mounted on the platen-frame and extending along the top of the platen parallel thereto, and a resilient paper-guiding and paper-holding finger 95 slidable along said finger-carrying bar so as to be adjusted along the platen, said finger being curved to the contour of the platen and extending downward at the front thereof, said finger at its lower end passing below and to the rear of the upper edge of the sheet-guiding bar so as to be 100 pressed towards the platen thereby, and having its ends outwardly turned to clear the edge of a work-piece as it is fed around the platen.

6. In a front-strike typewriting machine, 110 the combination with a platen-frame and a revoluble platen journaled therein, of a finger-carrying bar extending along the top of the platen parallel thereto, a resilient paper-guiding and paper-holding finger 115 slidable along said bar so as to be adjusted along said platen, said finger being curved to the contour of the platen and extending downwardly at the front thereof in paper-guiding and paper-holding relation thereto, 120 and connections at the ends of said bar passing to the rear and to the front of the platen for detachably rigidly mounting said bar on the platen-frame.

7. In a front-strike typewriting machine, 125 the combination with a platen-frame and a revoluble platen journaled therein, of a finger-carrying bar extending along the top of the platen parallel thereto, a rear bracket to which each end of the bar is secured, 130

means for detachably mounting said brackets on the platen-frame, a resilient paper-guiding and paper-holding finger slidable along said bar so as to be adjusted along the 5 platen, said finger being curved to the contour of the platen and extending downwardly at the front thereof in paper-guiding and paper-holding relation thereto, and other detachable engaging means on the bar passing 10 to the front of the platen for holding the bar rigidly in place.

8. In a front-strike typewriting machine, the combination with a platen-frame, a revoluble platen journaled therein, and paper-finger mounted on the platen-frame and extending upwardly at the front of the platen in spaced relation, of a finger-carrying bar extending along the top of the platen parallel thereto, a resilient paper-guiding and 15 paper-holding finger non-rotative upon and slidable along said bar so as to be adjusted along the platen, said paper-guiding and paper-holding finger being curved to the contour of the platen and extending downward at the front thereof in paper-guiding and paper-holding relation thereto, and a supporting bracket for the bar at each end thereof and to which the bar is rigidly secured, each said 20 bracket having a rearwardly-extending arm, means comprising a socket and a hook or prong for detachably securing the rear end of each said arm upon the platen-frame at the rear of the platen, each said bracket also 25 having a projecting front end part forming a hook opened at the front for detachably receiving said roll on the adjacent paper-finger when the latter is sprung away from the platen, said rolls on said paper-fingers serving to hold work-sheets on the 30 platen in the absence of said detachable card or label-holding device.

35 9. In a front-strike typewriting machine, the combination with a platen-frame, a revoluble platen journaled therein, and paper-fingers mounted on the platen-frame and extending upwardly at the front of the platen in spaced relation, of a finger-carrying bar 40 extending along the top of the platen parallel thereto, a resilient paper-guiding and paper-holding finger slidable along said bar so as to be adjusted along the platen, said 45 paper-guiding and paper-holding finger being curved to the contour of the platen and extending downward at the front thereof in paper-guiding and paper-holding relation thereto, a supporting bracket for the 50 bar at each end thereof and to which the bar is rigidly secured, each said bracket having a rearwardly-extending arm, means comprising a socket and a hook or prong for detachably securing the rear end of 55 each said arm upon the platen-frame at the rear of the platen, and forwardly-extending members for detachably securing each bracket to the upper end of the adjacent paper-finger for holding the finger-carrying 60 bar rigidly in place.

65 10. In a front-strike typewriting machine, the combination with a platen-frame, a revoluble platen journaled therein, resilient paper-fingers mounted on the platen-frame and extending upwardly at front of

the platen in spaced relation, and a roll carried by each paper-finger, of a detachable card or label-holding device comprising a finger-carrying bar extending along the top of the platen parallel thereto, a 70 resilient paper-guiding and paper-holding finger non-rotatable upon and slidable along said bar so as to be adjusted along the platen, said paper-guiding and paper-holding finger being curved to the contour of 75 the platen and extending downward at the front thereof in paper-guiding and paper-holding relation thereto, and a supporting bracket for the bar at each end thereof and to which the bar is rigidly secured, each said 80 bracket having a rearwardly-extending arm, means comprising a socket and a hook or prong for detachably securing the rear end of each said arm upon the platen-frame at the rear of the platen, each said bracket also 85 having a projecting front end part forming a hook opened at the front for detachably receiving said roll on the adjacent paper-finger when the latter is sprung away from the platen, said rolls on said paper-fingers serving to hold work-sheets on the 90 platen in the absence of said detachable card or label-holding device.

11. In a front-strike typewriting machine, the combination with a platen-frame, a revoluble platen journaled therein, and paper-fingers mounted on the platen-frame and extending upwardly at the front of the platen in spaced relation, of a card or label-holding device comprising a finger-carrying bar extending along the top of the platen parallel thereto, a resilient paper-guiding and paper-holding finger non-rotatably mounted on said bar and slidable along the 95 bar so as to be adjusted along the platen, said paper-guiding and paper-holding finger being curved to the contour of the platen and extending downwardly at the front thereof in paper-guiding and paper-holding relation thereto, a bracket on each 100 end of said bar and to which the bar is rigidly secured, a socket-forming member firmly mounted on the platen-frame at each side thereof at the rear of the platen, each 105 said bracket having a rearwardly-extending arm provided with a hook or prong detachably engageable in the socket formed by the corresponding socket member, and means for detachably supporting each of said brackets upon the upper end of the adjacent 110 paper-finger.

12. A card-holding or label-holding attachment for a revoluble platen front-strike typewriting machine having a platen-frame in which the platen is journaled, comprising 115 a bar to extend along the upper side of the platen parallel to the platen, means for rigidly detachably mounting the bar upon the platen-frame, a sheet-guide extending along the front of the platen below the printing 120 130

line, and paper-holding guide-fingers slideable along said bar and being curved around the front of the platen and extending downward below the sheet-guide.

5 13. A card-holding or label-holding attachment for a revoluble platen front-strike typewriting machine having a platen-frame in which the platen is journaled, comprising a bar to extend along the upper side of the platen parallel to the platen, means for rigidly detachably mounting the bar upon the platen-frame, a sheet-guide extending along the front of the platen below the printing line, slides adjustable along the bar, and curved paper-holding guide-fingers formed of relatively thin wire rigidly secured at their upper ends to said slides and extending downwardly around the front of the platen to a point below the printing line between the platen and the sheet-guide, the lower ends of said wire being outwardly turned to clear a card as it is fed around the platen.

10 14. In a front-strike typewriting machine, the combination with a platen-frame and a revoluble platen journaled therein, of a finger-carrying bar extending along the upper side of the platen parallel thereto, a resilient paper-guiding and paper-holding finger non-rotatably mounted on said bar and slideable along the bar so as to be adjusted along the platen, said paper-guiding and paper-holding finger being curved to the contour of the platen and being extended downward at the front thereof in paper-guiding and paper-holding relation thereto, a bracket on each end of said bar and to which the bar is rigidly secured, means for detachably connecting said brackets to the platen-frame at the rear of the platen, bracket-holding members mounted on the platen-frame at the front of the platen below the printing line and projecting upwardly at the front of the platen, and means for detachably connecting said brackets at the front of said bar to the upper ends of said bracket-holding members.

15 15. In a front-strike typewriting machine, the combination with a platen-frame and a revoluble platen journaled therein, of a finger-carrying bar extending along the upper side of the platen parallel thereto, a resilient paper-guiding and paper-holding finger non-rotatably mounted on said bar and slideable along the bar so as to be adjusted along the platen, said paper-guiding and paper-holding finger being curved to the contour of the platen and being extended downward at the front thereof in paper-guiding and paper-holding relation thereto, a bracket on each end of said bar and to which the bar is rigidly secured, means for

detachably connecting said brackets to the platen-frame at the rear of the platen, comprising a hook-and-socket connection disengageable by swinging said bar and its brackets upwardly and rearwardly and engageable by a reverse movement, upstanding resilient bracket-holding members mounted on the platen-frame at the front of the platen below the printing line, and a releasable catch-device for detachably connecting each said bracket with the corresponding upstanding member, said catch-device being releasable by substantially horizontal movement of the upper end of the corresponding upstanding member.

20 16. In a front-strike typewriting machine, the combination with a platen-frame and a revoluble platen journaled therein, of a finger-carrying bar extending along the upper side of the platen parallel thereto, a resilient paper-guiding and paper-holding finger non-rotatably mounted on said bar and slideable along the bar so as to be adjusted along the platen, said paper-guiding and paper-holding finger being curved to the contour of the platen and being extended downward at the front thereof in paper-guiding and paper-holding relation thereto, a supporting bracket for the bar on each end thereof and to which the bar is rigidly secured, each said bracket having a rearwardly-extending arm, for each said arm an upstanding bracket member rigidly mounted on the platen-frame at the rear of the platen, a detachable connection between each bracket arm and its corresponding bracket member adapted to be brought into interlocking relation by swinging said bar and its brackets forwardly and to be released by swinging said bar and its brackets rearwardly, upstanding bar-supporting members at the front of the platen adjacent the ends thereof mounted on the platen-frame below the printing line, and means including releasable catch-devices for releasably securing the ends of said bar to the upward ends of said upstanding members.

25 17. A card-holding attachment for a revoluble platen front-strike typewriting machine having a platen-frame in which the platen is journaled, comprising a bar to extend along the upper side of the platen parallel thereto, means for rigidly detachably mounting the bar upon the platen-frame, a paper-holding and guiding-finger slideable along said bar and curved around the front of the platen, and means to press the free end of said finger against the platen.

ALFRED G. F. KUROWSKI.
